UNITED STATES PATENT OFFICE

JAMES W. SALTER AND JAMES A. SALTER, OF BERKELEY, CALIFORNIA, ASSIGNEES TO COAST TO COAST AMUSEMENT ASSOCIATION, OF OAKLAND, CALIFORNIA

DESIGN FOR A GAME APPARATUS

Application filed May 26, 1930. Serial No. 35,778. Term of patent 14 years.

To all whom it may concern:

Be it known that we, JAMES W. SALTER and JAMES A. SALTER, both citizens of the United States, and both residents of Berkeley, in the county of Alameda and State of California, have jointly invented a new, original, and ornamental Design for Game Apparatus, of which the following is a specification, reference being had to the accompanying drawing, forming part thereof.

We claim:

The ornamental design for a game apparatus substantially as shown.

JAMES W. SALTER.
